(57) **CLAIM**

The ornamental design for a model vehicle chassis brace as shown and described.

DESCRIPTION

FIG. 1 is an upper, left, rear perspective view of a model vehicle chassis brace showing our new design;

FIG. 2 is an upper, right, front perspective view thereof;

FIG. 3 is a lower, left, rear perspective view thereof;

FIG. 4 is a lower, right, front perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is an upper plan view thereof; and,

FIG. 10 is a lower plan view of the model vehicle chassis brace.

In the drawings, the broken lines illustrate portions of the model vehicle chassis brace that form no part of the claimed design.
